UNITED STATES PATENT OFFICE.

WATSON SANFORD, OF NEW YORK, N. Y.

DESIGN FOR A HEATING-STOVE.

Specification forming part of Design No. 5,749, dated April 2, 1872.

To all whom it may concern:

Be it known that I, WATSON SANFORD, of the city, county, and State of New York, have invented and produced a new and original Design for a Stove, of which the following is a specification:

The nature of my design is represented in the accompanying photographic illustration, to which reference is had.

The new features of my invention consist in the form of outline and design of castings which form the top or cap of the stove, and the water-urn surmounting the same; also the circular middle portion of the stove, which is provided with a door and frames for holding isinglass, and the base of the stove.

These designs may be used either all together on one stove, as shown in the accompany-

ing photograph, or separately, as may be desired.

Claims.

What I claim as my invention is—

1. The new design of castings for the top or cap of a stove and urn surmounting same, substantially as shown and described.
2. The new design of casting for the circular middle portion of stove, substantially as shown and described.
3. The new design of casting for the base of a stove, substantially as shown and described.

W. SANFORD.
